UNITED STATES PATENT OFFICE.

TIMOTHY O'SHEA, OF CHICAGO, ILLINOIS.

BUILDING CONSTRUCTION.

SPECIFICATION forming part of Letters Patent No. 766,280, dated August 2, 1904.

Application filed August 31, 1903. Serial No. 171,326. (No model.)

To all whom it may concern:

Be it known that I, TIMOTHY O'SHEA, a citizen of the United States of America, residing at Chicago, in the county of Cook and State 5 of Illinois, have invented certain new and useful Improvements in Building Constructions, of which the following is a specification.

My invention relates to certain new and useful improvements in building constructions; and its object is to produce a structure which shall be strong, cheap, and easily assembled.

To this end my invention consists in certain novel features of construction, which are 15 clearly illustrated in the accompanying drawings and described in this specification.

In the aforesaid drawings, Figure 1 is a view, partly in elevation and partly in section, through a building embodying my improved 20 construction, showing a section through a wall, a girder, and a column. Fig. 2 is a section in the line 2 of Fig. 1 looking downward. Fig. 3 is a section in the line 3 of Fig. 2 looking in the direction of the arrow. Fig. 25 4 is a section in the line 4 of Fig. 3. Fig. 5 is a section through a modified floor construction. Fig. 6 is a section through a modified column-structure, and Fig. 7 is a perspective of the cap of one of the columns.

Referring to the drawings, A indicates a wall, which is composed of concrete and in which are embedded a plurality of vertically-extending spiral strips of sheet metal A'. Each 30 of these strips is preferably about four inches wide and is twisted with a half-turn about every foot. The spiral strips, it will be seen, are spaced about eighteen inches apart and are wired together by wires a. This structure makes an extremely solid and rigid wall and 35 one whose construction is extremely simple and cheap.

Transverse girders are constructed after the same manner as the walls as indicated in Figs. 1 and 3, the girders being indicated by B. 40 Horizontal strips of metal B', twisted into spirals like the strips A', are laid in tiers, the number depending upon the size of the girder. The girder shown herein is composed of six such strips laid in two rows, each three deep. 45 These girders are wired together by wires b, and anchored in the walls by anchors b', pass-

ing about the vertical strips A'. Columns can be constructed following this same general course of construction by taking a single strip C' and embedding it in a cylinder of concrete 55 to form a column C. A foundation-plate c, having a groove for the reception of the lower end of the spiral strip, is provided on which the column may be supported. The cap c' is provided at the top of the column, the spiral 60 strips passing through a slot c' in the cap and having a transverse rod or bolt c', which prevents relative longitudinal movement between the cap and the spiral strip.

When it is desired to construct a larger column, the method illustrated in Fig. 6 is followed, where one central spiral strip C' is used and a plurality of smaller strips C', surrounding the same. When such a structure is used, the large central strip C' passes through 70 the cap at the top, but the smaller strips C' terminate at the cap and aid in supporting its weight. Floors D can be constructed from this same spiral strip and concrete structure, the spiral strips being laid horizontally at intervals of about six inches and wired together by wires d. The ends of the strips are flattened out at d' and curved downward at d' over the edges of the girders. When this kind of flooring is used in connection with an 75 I-beam construction, the same method is followed except that the ends are curved down and under the flanges of the I-beams, as indicated at d', Fig. 5, after which the entire structure is embedded in the concrete. This 80 type of construction, it will be seen, forms a simple, strong, and easily-assembled structure. The metal strips can be twisted up into spirals very readily by machinery, and no difficulty is met with in working upon them in 85 any desired way.

I realize that considerable variation is possible in the details of this construction without departing from the spirit of the invention, and I therefore do not intend to limit 90 myself to the specific form herein shown and described.

I claim as new and desire to secure by Letters Patent—

1. In a building construction, the combination with suitable walls, girders and flooring, of a column comprising a concrete body and

a twisted strip of sheet metal embedded therein, a cap for the column below one of the girders, said cap being slotted for the passage of the strip of sheet metal and a cross-bar extending through the strip of sheet metal and adapted to prevent a downward movement of the cap and girder upon the strip of sheet metal.

2. In a building construction, the combination with suitable walls, girders, and floors, of a column comprising a body of concrete and a twisted strip of sheet metal of less diameter than the body of concrete and a foundation-plate having a groove adapted to receive the end of the twisted sheet.

3. In a building construction, the combination with suitable walls, girders, and floors, of a column comprising a body of concrete, a central twisted strip of sheet metal and a plurality of twisted strips arranged about said central strip. 20

In witness whereof I have signed the above application for Letters Patent, at Chicago, in the county of Cook and State of Illinois, this 26th day of August, A. D. 1903.

TIMOTHY O'SHEA.
